Primary Examiner — Paula Allen Greene*(74) Attorney, Agent, or Firm* — Raguraman Kumaresan(57) **CLAIM**

The ornamental design for a speaker microphone, as shown and described.

DESCRIPTION

FIG. 1 is a front perspective view of an ornamental design for a speaker microphone;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines immediately adjacent the surface shading represents the bounds of the claimed design while all other broken lines are directed to environment and are for illustrative purposes only, the broken lines form no part of the claimed design.

1 Claim, 7 Drawing Sheets(56)
